UNITED STATES PATENT OFFICE.

ALVIN D. KEENE, OF MANSFIELD, OHIO, ASSIGNOR TO WESTINGHOUSE ELECTRIC & MANUFACTURING COMPANY, A CORPORATION OF PENNSYLVANIA.

LEAD-POT SUPPORT.

Application filed February 16, 1927. Serial No. 163,576.

My invention relates to electric furnaces and more particularly to furnaces for heating lead pots.

In such furnaces it has been customary to provide a single flat ring secured at its outer edge to the furnace wall and the inner periphery of which engages the outturned rim of the lead pot in supporting relation.

There are two objections to supporting rings of this type. First, because of the unequal expansion of the inner and outer peripheries of the supporting ring, the outer periphery being relatively cool, it is common for the ring to become cracked or split radially, thereby making it unfit for further operation. Second, since a portion of this ring is exposed to the high temperature of the furnace chamber, it has been necessary to construct the ring from a suitable heat resistant material, such as nichrome, which is relatively expensive.

An object of my invention is the provision of a lead pot support which will not crack or split responsive to unequal expansion of different parts thereof.

Another object of my invention is the provision of a lead pot support of the required mechanical strength, but wherein the necessary amount of heat resistant material employed is reduced to a minimum.

Another object of my invention is the provision of a lead pot support of such construction that access to the furnace chamber and heating element is facilitated.

In practicing my invention, I provide a furnace of the resistor type, including a frame and suitable refractory walls and bottom, forming a chamber wherein is hung a resistor element. Supported on the top of said frame member and refractory material are a plurality of interfitting coaxial members or rings, the lateral sections of which are angularly disposed with respect to each other, and the inner periphery of the innermost ring engaging the outturned rim of the pot or container in supporting relation.

In the accompanying drawings, the figure shows an elevation in section, of a resistor furnace embodying my invention.

An electric furnace, designated generally as 10, comprises an outer frame or casing 11 inside of which layers of suitable refractory material 12 are located and arranged to form a furnace chamber 13. A ring 15, supported upon the refractory material, pro-

vides a support for resistor elements 14, which are suspended from ring 15 within said chamber by means of bolts 16. Upon the outer wall of said furnace is mounted a terminal box 17 for the leads 18 of the resistor. The particular construction of the heating unit constitutes no part of my invention and further detailed description thereof is believed to be unnecessary.

A substantially flat ring 19 is secured, at its outer periphery, to the wall of said furnace, as at 20, and is provided, at its inner periphery, with an upturned bead 21. An additional supporting and reinforcing means is provided, comprising a depending annular rib 22 formed integral with the ring 19 and resting upon the top of the refractory material. Concentric with the ring 19 is a second annular ring 23 provided at its outer periphery with an annular groove 24 for engagement with the bead 21 of the first ring. The inner periphery of said second ring is formed with an upturned portion 25, which engages in supporting relation the downturned annular rim 26 of a lead pot 27. The second ring is frustro-conical in shape, the lateral section of which is disposed upwardly at an angle to the plane of the first ring.

When the furnace is in operation, the inner periphery of ring 23 will be exposed to a greater amount of heat than the outer periphery, and an unequal expansion will result. In view, however, of the upward slant of the lateral section of this ring, the relatively great expansion at the inner periphery will merely deform that portion of the ring and the effect upon the cooler portions will be minimized. This deformation at the inner periphery of ring 23 therefore tends to raise the lead pot, which counteracts the normal tendency of the pot to pull down through the ring.

Mounted upon said second ring is a cover 30, a portion 31 of which is pivoted about a hinge bar 32 so that it may be swung back to permit charging of the lead pot. An abutment 33 is provided to support the hinged portion 31 in its open position. Suitable heat insulating material is disposed in the space between the interfitting rings and the top of the refractory material.

In the construction described, a lead pot support is provided, which, because of the angular relation of the lateral sections of

the rings, provides a supporting means of high mechanical strength, with a relatively small thickness of material, and obviates the tendency of the ring to crack or split responsive to unequal expansion thereof; and, since the only part exposed directly to the furnace temperature is a portion of ring 23, only this ring need be constructed of heat resistant material.

10 It will also be noted that, by the removal of ring 23, ready access may be had to the furnace chamber and heating elements, without necessitating the removal of ring 19.

While throughout the specification I have used the terms "ring" and "annular member" to designate each of the plate members 19 and 23, it is obvious that they may be of rectangular or elliptical configuration, depending upon the shape of the furnace wall 20 and lead pot, and be within the scope of my invention.

Various modifications may be made in the device embodying my invention without departing from the spirit thereof, and I desire that only such limitations shall be placed thereon as are imposed by the prior art, or are specifically set forth in the appended claims.

I claim as my invention:

20 1. A support for a high temperature container in a casing, comprising a plurality of co-axial annular members of different diameters, the inner periphery of one adapted to engage, in supporting relation, the outer periphery of a second, and means for removably maintaining said members in interfitting relation.

2. In a support for a high temperature container in a furnace, an annular member 40 the outer periphery of which is secured to the furnace wall, a second annular member frustro-conical in shape, the outer periphery of which is in interfitting relation with the inner periphery of the first annular member, an upwardly curved flange on said second member adapted to operatively engage a downwardly curved flange on said container to support the same.

3. Means for supporting a high temperature container comprising an outwardly rolled rim portion integral with said container, a frustro-conical member of relatively small altitude, the inner periphery of which operatively engages said rim portion and the outer periphery of which operatively engages a second annular member, said second annular member being disposed substantially horizontally and in operative engagement with a supporting structure.

4. In a high temperature container support, a furnace, an annular member constituting a portion of the top of said furnace

and fixed thereto, a second annular member, the lateral section of which extends upwardly at an angle to said first annular member, 65 means for positioning the outer periphery of said second member in operative engagement with the inner periphery of said first member, and means on the inner periphery of said second member for supporting said container.

5. Means for supporting a high temperature container in a casing comprising a flat annular member, the outer periphery of which is supported upon said casing, a second annular member co-axial with said first member, the lateral section of which is disposed upwardly at an angle to the plane of 75 said first annular member, means for removably maintaining the outer periphery of said second annular member upon the inner periphery of said first annular member, and means on said container for operative engagement with the inner periphery of said second member.

6. Means for supporting a high temperature container, comprising a downwardly curved rim portion, a co-axial annular member having an upwardly curved lateral section whose inner peripheral portion operatively engages the rim portion, and a second co-axial annular member whose lateral section is substantially plane and whose inner rim portion operatively engages the outer rim portion of the first named co-axial 90 annular member, and a co-axial casing for supporting all of said members and the container.

7. In a support for a high temperature container in a furnace, the combination with 100 a furnace wall, a flat annular member secured to and co-extensive with said furnace wall, means for supporting said member above said wall to provide a space for heating insulating material, a second annular 105 member coaxial with the first, interfitting means carried by the inner periphery of the first member and the outer periphery of the second to removably support the second member upon the first, and means carried by the 110 inner periphery of said second member to engage an outwardly turned rim on said container in supporting relation.

8. A support for a high temperature container in a furnace, comprising a plurality of 115 co-axial peripheral plates, means for supporting the outer periphery of one plate upon the inner periphery of another, and means for removably maintaining said members in interfitting relation.

In testimony whereof, I have hereunto subscribed my name this 11 day of February, 1927.

ALVIN D. KEENE.
